UNITED STATES PATENT OFFICE

HERBERT HENRY BERRY, OF LONDON, ENGLAND

ELECTRIC HEATING ELEMENT

Application filed September 1, 1928, Serial No. 303,523, and in Great Britain October 28, 1927.

This invention relates to electric heating elements for electric radiators, fires, and the like, and with which a resistance wire of spiral formation is used.

5 One object of the invention is to provide improved supporting means for such resistance wires and which will prevent excessive local heating of the wires.

Another object of the invention is to provide 10 a support for such resistance wires which prevents excessive lateral displacement and consequent contacting of adjacent coils of the wires.

With these and other objects in view I 15 construct the support in one or more pieces, or sections usually in several sections, with spaced projections adapted to enter between the convolutions of the wire.

In the drawings:—

20 Fig. 1 is a perspective view of a supporting section with a projection formed integrally with the said section.

Fig. 2 is a plan view of two supporting sections with projections between them,

25 Fig. 3 is an end view of same and

Fig. 4 is a plan view of part of a heating element constructed from the said sections having projections provided between some of them.

30 In Fig. 1 the section 1 has three grooves 2 in which the usual helical resistance wire, not shown, is placed when the element is built up in substantially known manner and at an end of each of the grooves is formed

35 an integral fin-like projection 3 which, in the completed element, enters between two coils of the resistance wire and holds same against longitudinal displacement. Sections such as 1 with the fin-like projections are 40 preferably placed at intervals in the built-up element, the other sections not having the fins.

In Figs. 2 to 4 the sections are of substantially known type and the projections 5 are 45 provided between them. The said projec-

tions consist of strips of mica or like insulating and heat-resisting material which are placed at intervals, see Fig. 4, between two sections and are held in place by bolts 6 passing through holes such as 7 in the sections and strips. When the resistances such as 8 are put in place in grooves 9 the projections enter between some of the coils and hold the resistance against longitudinal displacement.

55 The element shown in Fig. 4 has parts 10 arranged to form front supporting arms for the resistance wire and I have found the combination of these arms and the projections very satisfactory in use since the arms 10 and projections 5 collectively hold the wire very securely in place under all ordinary conditions.

60 What I claim is:—

1. A support for the resistance wires of 65 electric radiators comprising a plurality of sections, each of which is formed with a series of grooves, means for securing the sections together to longitudinally align the similar grooves of the respective sections, 70 and insulating heat resisting strips secured by said means between adjacent sections, said strips having their upper edges projecting beyond the wire-receiving surfaces of the grooves to thereby provide projections 75 extending transversely of the grooves to engage between the convolutions of the resistance wires for holding the wires against longitudinal displacement.

2. A support for the resistance wires of 80 electric radiators comprising a plurality of sections, each of which is formed with a series of grooves, means for securing the sections together to longitudinally align the similar grooves of the respective sections, 85 insulating heat resisting strips secured by said means between adjacent sections, said strips having their upper edges projecting beyond the wire-receiving surfaces of the grooves to thereby provide projections ex- 90

tending transversely of the grooves to engage between the convolutions of the resistance wires for holding the wires against longitudinal displacement, and members secured between adjacent sections by said means and formed with projections to overlie each of the grooves formed by the aligned sections for retaining the resistance wire against outward displacement.

10 In testimony whereof I affix my signature.
HERBERT HENRY BERRY.
